UNITED STATES PATENT OFFICE.

LEON COHN, OF PARIS, FRANCE.

DESIGN FOR A BOTTLE.

Application filed September 26, 1923. Serial No. 7,341. Term of patent 7 years.

To all whom it may concern:

Be it known that I, LEON COHN, a citizen of the United States of America, residing in the city of Paris, France, trading as Parfumerie Forest, have invented a new, original, and ornamental Design for a Bottle, of which the following is a specification, reference being had to the accompanying drawing, forming a part thereof.

In the drawing,

Fig. 1 shows a perspective view of the bottle,

Fig. 2 is a side view thereof.

Fig. 3 is a top view thereof.

I claim:

The ornamental design for a bottle substantially as shown.

LEON COHN.
